US00D901446S

(12) **United States Design Patent** (10) **Patent No.:** **US D901,446 S**
Lee (45) **Date of Patent:** **** Nov. 10, 2020**

(54) **CONTROLLER FOR VEHICLE VIDEO RECORDER**

(71) Applicant: **THINKWARE CORPORATION**, Gyeonggi-Do (KR)

(72) Inventor: **Yong Lee**, Seoul (KR)

(73) Assignee: **THINKWARE CORPORATION**, Gyeonggi-do (KR)

(**) Term: **15 Years**

(21) Appl. No.: **29/644,734**

(22) Filed: **Apr. 20, 2018**

(30) **Foreign Application Priority Data**

Jan. 4, 2018 (KR) 30-2018-0000531

(51) **LOC (12) Cl.** **14-03**

(52) **U.S. Cl.**

USPC **D14/218**

(58) **Field of Classification Search**

USPC D14/218; D13/168

See application file for complete search history.

(57) **CLAIM**

The ornamental design for a controller for vehicle video recorder, as shown and described.

DESCRIPTION

FIG. 1 is a perspective view of a controller for vehicle video recorder showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top view thereof; and,

FIG. 7 is a bottom view thereof.

The broken lines depict portions of the controller for vehicle video recorder that form no part of the claimed design.

1 Claim, 7 Drawing Sheets
